UNITED STATES PATENT OFFICE

MARSDEN H. LANDERS, OF SYRACUSE, NEW YORK, ASSIGNOR TO THE LAMSON COMPANY, OF SYRACUSE, NEW YORK, A CORPORATION OF MASSACHUSETTS

CENTRAL STATION APPARATUS

Application filed December 30, 1929. Serial No. 417,393.

This invention relates to an improvement in a central station apparatus for carrier despatch systems to which are sent carriers from the various out-stations containing cash, charge slips, and other memoranda, at which the contents of the carriers are handled by the clerks at the central station, and from which the carriers are returned to the station from which they were sent or despatched to other places.

The central station apparatus to which this invention is directed comprises briefly a main receiving desk at which all the carriers are received, work tables to which the carriers are delivered from the main desk and where their contents are properly handled and a despatching desk to which the carriers are sent from these tables and from which they are despatched to the proper out-stations.

20 The primary object of this invention is to provide suitable means at the work tables usually designated as cash and credit or cashiers' or authorizers' stations, for handling the carriers and by which a rapid increase or decrease in the personnel at the tables is possible in response to the amount of business done and the work thereat is facilitated.

In the accompanying drawings is illustrated one embodiment of this invention by way of example and in these drawings:

Fig. 1 illustrates somewhat diagrammatically a plan view of a central station apparatus embodying this invention;

Fig. 2 is an end view taken from the left of Fig. 1 illustrating the manner in which the carriers are delivered to the main delivery desk and distributed therefrom;

Fig. 3 is an elevational view of one of the charge or credit tables;

40 Fig. 4 is a plan view of such table;

Fig. 5 is an enlarged view partially in section illustrating the mechanism by which the carriers are delivered to a station at the table;

45 Figs. 6 and 7 are side elevations illustrating one detail of this invention in two positions; and

Fig. 8 is a side elevation somewhat diagrammatic illustrating another embodiment of this invention.

50 The central station illustrated in Fig. 1

comprises a main receiving desk A which may be of the general type illustrated in the Whittier Patent No. 1,365,428, dated January 11, 1921. Associated with the main receiving desk A are a plurality of cash tables B and a plurality of credit tables C. Connected to each of these tables B and C is a despatcher's desk D to which the various carriers are sent from the tables and from which these carriers are despatched to their proper destination.

The carriers are delivered to the main receiving desk A through a plurality of despatch tubes 10; one of which is shown in Fig. 2. In the usual mercantile establishment for which this system is adapted the carriers sent to the desk A contain either cash or credit memoranda and in order to speed up the system as much as possible the cash carriers are sent to table or tables B while the credit carriers are sent to table or tables C. One way

55 of separating the carriers into these groups is to provide each tube 10 with a separator 11 which may be of any desired form such as, for example, that shown in the patent to Pearsall, No. 1,102,225, dated June 30, 1914,

70 so that the cash carriers arriving through the tube 10 are delivered to the desk through branch tubes 12 and the credit carriers are delivered through branch tubes 13. The carriers traveling through the tubes 12 and 13

75 are delivered to conveyor belts 14 and 15 respectively which, as shown particularly in Fig. 1, extend the entire length of the main receiving desk A at either side of the delivery tubes. The conveyors 14 and 15 are caused

80 to travel in the directions indicated by the arrows in Fig. 1 by any suitable means, no means being here shown. From the conveyors 14 and 15 the carriers are led to the various tables B and C.

85 As shown in Fig. 1 the carriers on the conveyor 14 are led to the tables B while the carriers on the conveyor 15 are led to the table C. The carriers are diverted from the conveyors 14 and 15 into gravity chutes 16 and 17 re-

90 spectively, by which they are delivered through despatch tubes 18 and 19 to the proper tables. As shown in Fig. 1 there are a plurality of chutes 16 and 17 arranged along the

95 length of the table A. Each of these tubes

is provided with a manually operable switch 20 so that they may be either opened or closed. In Fig. 1 the switch of two of the chutes 16 and of two of the chutes 17 are open while those of the third are closed. Thus carriers are being sent to both tables B and tables C. The intermediate chutes 16 and 17 lead to other tables not shown.

The carriers diverted by the switches 20 to the various tables are handled in the same manner, and accordingly one table only will be described in detail. (See Figs. 3 to 7 inclusive.) As shown in Fig. 4 the selected table B is provided with four chairs one for each clerk or operator. In front of each chair is mounted on the table an inclined carrier chute 21 to which the carriers are delivered from the tube 18. The tube 18 terminates at its outer end in a sleeve 22 from which a pipe 23 leads to a vacuum drum 24 or similar source of minus pressure. From the end of the sleeve 22 extends a continuation tube 25 which is normally cut off from the tube 18 by a spring closed gate 26. A carrier arriving at the sleeve 22 opens the gate 26 by its impact and passes on by gravity through the sleeve into the continuation tube 25. The continuation tube 25 opens into a passage through one arm 30 of a Y-shaped member 31 supported upon a revolvable shaft 32 which extends through the center of the table. The shaft 32 is mounted in a suitable bearing 33 on the floor or platform, is rotatable relative to the tube 25 in bearings 34 and is driven by a suitable motor 35.

To the arm 30 of the member 31 is secured a magazine tube 36 which forms a continuation of the passage therein and is supported at its lower end by an arm 38 carried by the revolvable shaft 32. The arm 38 also supports a carrier receiver 39 pivotally swung at its upper end on diametrically arranged pins 40. The receiver 39 is thus free to swing on these pins so that its upper end is out of alignment with the magazine tube 36. The carrier arm 38 is provided at its outer end with an extension 41 which terminates in a finger 42 extending below the bottom of the receiver 39 and normally preventing the passage of a carrier therethrough.

The chute 21 is preferably open at one side and extends downwardly at an angle terminating in a pocket 44. Mounted upon a suitable supporting frame 45 are a pair of brackets 46 and a bracket 47 which carry a shaft 48 to which is fixed a yoke 49. The yoke 49 is located between the brackets 46 while the bracket 47 may be extended to act as a support for the upper end of the chute 21. Between the arms of the yoke 49 is mounted a trip 50 secured upon a rotatable pin 51. A suitable spring surrounding the pin 51 holds the trip 50 normally in upright position but permits it to swing under excess pressure. On the side of the receiver 39 is mounted a

knob or projection 52 so located that it will, under normal conditions, engage the trip 50. Fixed upon the shaft 48 is an arm 53 normally held by a spring 54 in such position that the trip 50 will be held in position to be engaged by the projection 52. A link 55 connects the arm 53 to a lever 56 pivotally mounted upon a bracket 57 carried by the table B. The tip 58 of the lever extends through a slot 59 in the wall of the chute 21 above the bottom of the pocket 44 so that it will be engaged by a carrier in the chute. As will be clearly apparent from an examination of Fig. 5, a carrier in the chute 21 will depress the tip 58 of the lever 56 and acting through the elements just described will swing the trip 50 into a position in which it will no longer be engaged by the projection 52.

After the contents of a carrier have been properly handled the carrier is sent to the despatching desk D by the operator at the table. This may be done by providing one or more despatch outlets at each table or by other similar means. The means here shown has proven to be satisfactory and will therefore be described. Adjacent each chute 21 is formed in the table an opening 60 through which carriers may be dropped onto a rotating trough 61. The rotating trough 61 includes an inner circular wall 62 which forms, with a wall 63 downwardly projecting from the face of the table, an annular pocket. The trough 61 is connected by bars 65 with the rotating shaft 32 so that as the shaft rotates the trough also rotates and the carriers therein are brought to a pick-off chute 66 from which they pass to the despatcher's desk through a tube 67. The tubes arriving at the despatcher's desk D are returned by the operator through the despatch openings 70 to their destination.

From the description above given it will be clear that the carriers coming in from the various out-stations are separated and delivered at the main receiving desk A onto the conveyors 14 and 15. From these conveyors they pass through suitable chutes 16 and 17 and tubes 18 and 19 to the cash and charge stations B and C. By reason of the deflectors 20 it is possible to regulate the number of stations to be used both for cash and credit, and where there is little business only the chutes 16 and 17 at the left of Fig. 1 will be employed together with the tables B and C which they feed. However, as is the usual case, should the number of cash transactions be much greater than the number of charge transactions, one or more of the chutes 16 may be opened while only one of the chutes 17 would be open.

The carriers delivered through the tube 18 or 19 to the magazine tube 30 and thence to the receiver 39 are distributed automatically one to each of the chutes 21 on the table. It will be noted that while the magazine tube

36 is large enough to contain several carriers, the receiver 39 can only accommodate one. The receiver 39 is of such dimension that the upper end of a carrier therein resting upon the finger 42 prevents the bottom carrier in the magazine tube from projecting into the receiver. As the arm is rotated by the shaft 32 the projection 52 on the receiver 39 engages the trip 50 associated with the first chute which acts to swing the receiver on its pivots 40 away from the finger 42 so that the carrier will fall by gravity into the chute 21. As soon as the arm has passed the trip 50 the receiver 39 returns to the normal position and a second carrier falls from the magazine tube 36 thereinto. Thus by the time the receiver 39 arrives at the succeeding chute it contains a carrier which is delivered in the manner just described.

20 Whenever, in dull periods it is not even necessary to provide a clerk at each chute of a table a dummy carrier is placed in each unattended chute, and the trip 50 thereof will then be swung out of its normal position so that it does not engage the projection 52 on the receiver 39 as it passes by to release a carrier. It will be noted that the carriers are normally delivered seriatim to the chutes which are empty and are not delivered to 25 the filled chutes. Thus a very flexible condition is provided so that the work can quickly and be easily handled and the size of the force employed increased or diminished in accordance with the requirements that may 30 exist at any time.

The embodiment shown in Fig. 8 illustrates a small installation in which the carriers from the various out-stations are delivered onto a main desk which has only a single 40 conveyor thereon and from which they are transferred through a suitable chute to a pneumatic conveyor tube 80. The carriers have not previously been separated but are distributed by the separator 81 so that one 45 class of carriers will fall into the magazine tube 82, while the other class will pass on through a tube 83 to a second magazine tube 84. The carriers are delivered from the magazine tubes to the various chutes at the tables 50 in the manner previously described.

The cash and credit tables B and C are here shown as adjacent the main receiving desk but it will be readily understood that this is not essential and that the tables may 55 be located in separate compartments on the same or other floors wherever it is most convenient and desirable. Moreover the tables may be of any desired size and the number of chairs and operators provided are not limited to the four here shown.

I claim:

1. A central station apparatus comprising a work table having a plurality of operators' stations, a pneumatic despatch tube by which 65 carriers are despatched to the work table, a

carrier chute at each operator's station, and rotatable means for automatically feeding the carriers in the tube seriatim to the chutes.

2. A central station apparatus comprising a work table having a plurality of operators' stations, a pneumatic despatch tube by which carriers are despatched to the work table, a carrier chute at each operator's station, means including a rotatable magazine to which the carriers are delivered by the tube 70 for automatically feeding the carriers in the tube seriatim to the chutes, and mechanism for preventing the operation of said means with respect to certain predetermined chutes.

3. A central station apparatus comprising a work table having a plurality of operators' stations, a pneumatic despatch tube in which carriers are despatched to the work table, a carrier chute at each operator's station, means for automatically feeding the carriers in the tube seriatim to the chutes and mechanism for preventing the operation of said means with respect to chutes already containing carriers.

4. A central station apparatus comprising a work table having a plurality of operators' stations, a pneumatic despatch tube in which carriers are despatched to the work table, a carrier chute at each operator's station, a magazine tube into which the carriers in the despatch tube pass, a carrier receiver into which the magazine tube feeds the carriers, means for passing said receiver relative to the chutes, and means coacting with the receiver 80 whereby the carriers are delivered into the chutes from the receivers.

5. A central station apparatus comprising a work table having a plurality of operators' stations, a pneumatic despatch tube in which carriers are despatched to the work table, a carrier chute at each operator's station, a magazine tube into which the carriers in the despatch tube pass, a carrier receiver into which the magazine tube feeds the carriers, means for passing said receiver relative to the chutes, and means associated with each chute and coacting with the receiver whereby the carriers are delivered into the chutes from the receivers.

6. A central station apparatus comprising a work table having a plurality of operators' stations, a pneumatic despatch tube in which carriers are despatched to the work table, a carrier chute at each operator's station, a magazine tube into which the carriers in the despatch tube pass, a carrier receiver into which the magazine tube feeds the carriers, means for supporting and rotating said magazine tube and receiver as a unit relative to 100 the chutes, and means coacting with the receiver while in rotation whereby the carriers are delivered into the chutes from the receiver.

7. A central station apparatus comprising 105

- a work table having a plurality of operators' stations, a pneumatic despatch tube in which carriers are despatched to the work table, a carrier chute at each operator's station, a 5 magazine tube into which the carriers in the despatch tube pass, a carrier receiver into which the magazine tube feeds the carriers, means for supporting and rotating said magazine tube and receiver as a unit relative to 10 the chutes, and means associated with each chute coacting with the receiver while in rotation whereby the carriers are delivered from the receiver, one carrier falling into each chute.
- 15 8. A central station apparatus comprising a work table having a plurality of operators' stations, a pneumatic despatch tube in which carriers are despatched to the work table, a carrier chute at each operator's station, a 20 magazine tube into which the carriers in the despatch tube pass, a carrier receiver into which the magazine tube feeds the carriers, means for supporting and rotating said magazine tube and receiver as a unit relative to 25 the chutes, and means associated with each chute coacting with the receiver while in rotation whereby the carriers are delivered from the receiver, one carrier falling into each chute, said means being operative only 30 when the chute associated therewith is empty.
9. A central station apparatus comprising a work table having a plurality of operators' stations, a pneumatic despatch tube in which carriers are despatched to the work table, a carrier chute at each operator's station, a 35 magazine tube into which the carriers in the despatch tube pass, a carrier receiver into which the magazine tube feeds the carriers, means for supporting and rotating said magazine tube and receiver as a unit relative to 40 the chute, said receiver being pivotally mounted on such means and means coacting with the receiver while in motion for swinging the same and causing it to deliver a carrier into each chute.
- 45 10. A central station apparatus comprising a work table having a plurality of operators' stations, a pneumatic despatch tube in which carriers are despatched to the work table, a carrier chute at each operator's station, a magazine tube into which the carriers in the despatch tube pass, a carrier receiver into which the magazine tube feeds the carriers, means for supporting and rotating said 50 magazine tube and receiver as a unit relative to the chute, said receiver being pivotally mounted on such means, and means associated with each chute and coacting with the receiver while in motion for swinging the same and causing it to deliver a carrier into each chute.
- 55 11. A central station apparatus comprising a work table having a plurality of operators' stations, a pneumatic despatch tube in which carriers are despatched to the work table, a 60 magazine tube into which the carriers in the despatch tube pass, a carrier receiver into which the magazine tube feeds the carriers, a rotatable shaft by which the magazine tube and receiver are supported and rotated as a unit relative to the chutes, said receiver being pivotally mounted and normally in alignment with the tube, a projection upon the receiver, and a trip associated with each chute adapted to engage the projection on the receiver and to tilt the same out of its normal position as it passes the chute whereby the carrier in the receiver is free to fall into the chute.
- 65 12. A central station apparatus comprising a work table having a plurality of operators' stations, a pneumatic despatch tube in which carriers are despatched to the work table, a carrier chute at each operator's station, a 70 magazine tube into which the carriers in the despatch tube pass, a carrier receiver into which the magazine tube feeds the carriers, a rotatable shaft by which the magazine tube and receiver are supported and rotated as a unit relative to the chutes, said receiver being pivotally mounted and normally in alignment with the tube, a projection upon the receiver, and a trip associated with each chute 75 adapted to engage the projection on the receiver and to tilt the same out of its normal position as it passes the chute whereby the carrier in the receiver is free to fall into the chute.
- 80 13. A central station apparatus comprising a work table having a plurality of operators' stations, a pneumatic despatch tube in which carriers are despatched to the work table, a carrier chute at each operator's station, a magazine tube into which the carriers in the despatch tube pass, a carrier receiver into which the magazine tube feeds the carriers, and receiver are supported and rotated as a 85 unit relative to the chutes, said receiver being pivotally mounted and normally in alignment with the tube, a projection upon the receiver, and a trip associated with each chute 90 adapted to engage the projection on the receiver and to tilt the same out of its normal position as it passes the chute whereby the carrier in the receiver is free to fall into the chute, the receiver upon passing the trip resuming its normal position whereupon a 95 carrier falls from the magazine tube into the receiver.
14. A central station apparatus comprising a work table having a plurality of operators' stations, a pneumatic despatch tube in which carriers are despatched to the work table, a carrier chute at each operator's station, a magazine tube into which the carriers in the despatch tube pass, a carrier receiver into which the magazine tube feeds the carriers, said receiver being tubular in form to 100 accommodate one carrier only at a time, a rotatable shaft upon which the upper end of the magazine tube is supported, an arm fixed upon said shaft and acting to support fixedly the lower end of the magazine tube and pivotally the receiver, at its upper end a finger on said arm, said receiver being normally in alignment with the tube and the finger acting to close the lower end of the receiver, a projection on the receiver adjacent its lower end, and a trip associated with each chute which, as the tube and receiver are rotated, engages the projection on the receiver and tilts out of its normal position over the finger 110 115 120 125 whereupon the carrier therein falls into the chute.
15. A central station apparatus comprising a work table having at least one operator's station and means for delivering car- 130

riers to said station, which means include a pneumatic despatch tube, a magazine tube at the table, a carrier chute and means automatically delivering a carrier from the 5 magazine tube to the chute when the latter is empty.

15. A central station apparatus comprising a work table having at least one operator's station and means for delivering carriers to said station, which means include a pneumatic despatch tube, a magazine tube at the table, a carrier chute and a carrier receiver intermediate the magazine tube and the chute to which receiver a carrier is delivered 10 from the magazine tube and by which the carrier is delivered to the chute when the latter is empty.

16. A central station apparatus comprising a work table having at least one operator's station and means for delivering carriers to said station, which means include a pneumatic despatch tube, a magazine tube at the table, a carrier chute, a rotatable shaft on which said magazine tube is mounted, and a 25 carrier receiver also mounted on the shaft to which a carrier is delivered from the magazine tube and by which the carrier is delivered to the chute.

17. The combination with a work table 30 having an opening therein, a rotatable trough below said opening which receives carriers dropped through the opening, a pick-off chute and means for rotating the trough whereby the carriers thereon are delivered 35 to the chute.

18. A central station apparatus comprising in combination means by which carriers are despatched thereto, said means including a separator by which the carriers are divided 40 into groups, a plurality of work tables each having a plurality of operator's stations, and automatic means for despatching the carriers of one group to the operator's stations at one of said tables and the carriers 45 of another group to the operator's stations at another of said tables, said automatic means including at each table a rotatable magazine acting to distribute the carriers among the various operator's stations 50 at the table.

19. A central station apparatus comprising in combination a work table at which carriers of one group are handled, a second work table at which carriers of another group are 55 handled, each of said tables having a plurality of operator's stations, automatic means at each table for distributing the carriers to the various stations, a carrier separator and tubes by which the carriers are fed to the 60 separator and by which the separated carriers are fed to the automatic distributing means at each table.

Signed by me at Syracuse, New York, this thirtieth day of November, 1929.

65 MARSDEN H. LANDERS.
